UNITED STATES PATENT OFFICE.

KARL WEISS, OF WATERBURY, CONNECTICUT

REVOLVING PLIERS.

No. 852,479.

Specification of Letters Patent.

Patented May 7, 1907.

Application filed October 3, 1906. Serial No. 337,265.

To all whom it may concern:

Be it known that I, KARL WEISS, a citizen of the United States, residing at Waterbury, in the county of New Haven and State of Connecticut, have invented a new and useful Improvement in Revolving Pliers, of which the following is a specification.

This invention relates to pliers especially adapted for wire workers and the object of 10 the invention is a set of pliers, the jaws of which can be rotated independent of a rotary movement of the handles, so that in twisting wires it is not necessary to release the grip each half turn in order to take a new grip 15 and continue the twisting step by step. The pliers are also useful in working in corners or other places where it will be difficult to manipulate the ordinary pliers as the jaws can be operated by the handle levers in any position.

The invention consists of a pair of movable gripping jaws provided with cutters and turning upon a common pivot pin, of a movable cam block adapted to be forced in a 20 straight line between the inner ends of the jaws which are divergent and provided with rollers and a pair of handle levers rotatable with respect to the jaws and cam block, together with suitable means for inclosing the 25 cam block and holding the parts in their assembled position.

In the accompanying drawings—Figure 1 is a side elevation of the pliers, the jaws being shown open; Fig. 2 is a plan view of the 30 pliers; Fig. 3 is a section on the line $x-x$ of Fig. 2, the jaws being shown in open position; Fig. 4 is a section on the line 4—4 of Fig. 3; Fig. 5 is a section on the line $x-x$ of Fig. 2, the jaws being shown in closed position; Fig. 6 is a section on the line 6—6 of Fig. 3; Fig. 7 is a section on the line 7—7 of Fig. 3; Fig. 8 is a detail perspective view of one of the 40 jaws; Fig. 9 is a perspective view of the cam block; Fig. 10 is a perspective view of a sleeve rotating upon the cam block when in 45 position; Fig. 11 is a detail perspective view of the inner end of one of the handle levers; Fig. 12 is a detail perspective view of one section of a casing; Fig. 13 is a perspective view 50 of a flanged collar.

The pliers comprise the following essential parts namely a pair of co-operating jaws A, a cylindrical casing B split diametrically and serving as a holder for the jaws and also as a 55 casing or housing for a movable cam block C. A sleeve D is rotatably held upon the cam

block C and within the casing B and is adapted for rotation relative to rotation of the casing, jaws or cam block. Operating lever handles E adapted to engage and operate the 60 cam block are held in their proper position by means of a knurled and flanged collar F. The above are the essential features of the device and their construction will be described in detail.

Each jaw A is provided with a bifurcated portion A' adjacent its rear end in which portion is arranged a pin A² and this pin projects up each side of the jaw. In the bifurcated portion A' a roller G is mounted upon 70 the pin A². The jaws are divergent at their inner end portions, being provided with oppositely inclined cam faces A³ and adjacent said cam faces the opposing faces of the jaws are provided with suitable semicylindrical 75 bearings A⁴. To hold these jaws in position the casing B is provided with forwardly extending parallel ears B' and a suitable bolt J passes through these ears and the bearings A⁴ of the jaws A turn or work upon this bolt 80 J, which forms a common pivot pin for both of the jaws. The bolt J is held in position by an ordinary nut J'. To further aid in holding the jaws in position and also to hold them normally open, springs H are connect- 85 ed at one end to the pivot pin A² of one of the jaws and at the opposite end to the pivot pin A² of the other jaw. The casing B is split diametrically in order to facilitate the assembling of the parts mentioned and each 90 section is provided with a circumferential interior shoulder B² which terminates short of the edges of the section so that when the two sections are placed together they form a cylinder provided with opposing shoulders 95 on opposite sides of the cylinder, the ends of which are spaced apart. The cam block C consists of a disk C' of less diameter than the casing B and which carries upon its front face the cam block proper. This cam block 100 has its forward end V-shaped, thereby forming two oppositely inclined cam faces C², which faces are adapted to engage respectively the cam faces A³ of the jaws A. The cam block C also carries two outwardly and 105 oppositely arranged shoulders C', which fit in the spaces between the ends of the shoulders B², thereby preventing rotation of the cam block within the casing B and independent of rotation of the casing. The cam 110 block C is preferably core out, as shown in the drawing, in order to reduce as much as pos-

sible the weight of the pliers. A smooth cylindrical sleeve D fits within the casing B and bears against the rear faces of the shoulders B². The sleeve D has two oppositely arranged lugs D which project rearwardly from the casing B when the sleeve D is in position. It may also be noted that the sleeve D fits in the casing B between the casing and the disk C' of the cam block and rotates upon said 10 disk. Each handle lever E is provided at its inner end with a flat curved cam E', which cam carries a laterally extending pin E² projecting upon both sides of the cam and which serves as a movable pivot upon which the levers work. The collar F is provided with a retaining flange F' at its rear end and is threaded upon the rear end portion of the sleeve B. The cams E' of the handle levers E rest loosely within the collar F and between the lugs D' of the rotatable sleeve D and bear upon the rear face of the disk C'. The pivot pins E² bear upon the flange F' of the collar F when the jaws are in a closed position. Suitable cutting blades K are carried by one side of the jaws A.

From the above description it is thought that the operation of the pliers will be obvious. The handles E rotate loosely in the sleeve F and are held in the proper position 30 by means of the lugs D' of the sleeve D and this sleeve rotates freely within the casing B. When the handles E are pressed together the cams E' engage the smooth flat rear face of the disk C', forcing the same forwardly, and 35 the cam block C slides forwardly between the shoulders B² and the cam faces C² engage the cam faces A³ and force the rear ends of the jaws A apart, thus bringing the outer ends of the jaws together. It will be obvious as 40 there is no positive connection between the cams E' and the disk C' the jaws will be operated no matter what position is assumed by the handle relative to the jaws and the jaws may be operated during rotation of 45 either the jaws or the handle as well as while the parts are stationary.

It will be obvious that while the main object of the invention is to make the jaws rotatable with respect to the handle, the handle can also be rotated without imparting rotation to the jaws in case it is desirable to shift the position of the handles in order to get a better grip.

Having thus described my invention what 55 I claim as new and desire to secure by Letters Patent is—

1. A device of the kind described comprising a pair of gripping jaws, and a pair of operating handles adapted to operate said jaws, 60 and means for rotating the jaws independent of movement of the handles.

2. A revolving plier comprising two gripping jaws, two operating handles, and means for rotatably connecting the said jaws to the 65 said handles.

3. A device of the kind described comprising two gripping jaws having rear cam faces, a casing to which said jaws are connected, a cam block slidably held in said casing and adapted to engage the cam faces of the jaws, 70 handles having cam portions adapted to loosely engage the cam block, and a flanged collar loosely connecting said handles to a casing, the jaws, cam block and casing being rotatable relative to the handle. 75

4. A device of the kind described, a pair of gripping jaws having divergent cam faces, a casing supporting said jaws, a V-shaped cam block slidably held in said casing and adapted to engage the jaws, said cam block being provided with a rear disk portion, a flanged collar carried by the casing and operating handles having their inner ends provided with cams, said handles being loosely held within the collar and the cam ends of the handles 80 loosely engaging the disk of the cam block, as and for the purpose set forth. 85

5. A plier comprising two jaws working upon a common pivot point and provided with divergent rearwardly extending cam faces, a casing supporting and partially inclosing said jaws, a cam block loosely held in said casing and adapted to be brought into engagement with the cam faces of the jaws, means for preventing rotation of the cam 90 block independent of rotation of the casing, operating handles having inner cam ends in loose engagement with the rear face of the cam block and adapted to force the same forwardly when the handles are brought together, and means for holding the said handles in position and for the purpose set forth. 95

6. A device of the kind described comprising spring opened gripping jaws, a casing to which said jaws are attached, a cam slidably held in said casing, a sleeve rotatably held in the casing and having rearwardly projecting lugs, a flanged retaining collar carried by the rear of the casing and operative handles having cam ends and integral pivot pins loosely held within said retaining collar, the cam ends being loosely held between the lugs of the sleeve and a loose engagement with the rear face of the cam operating upon the jaws, as and for the purpose set forth. 100 105 110 115

7. Pliers of the kind described, comprising a casing having forwardly extending ears, a bolt fastened through said ears, gripping jaws having oppositely inclined rear cam faces and bearings formed adjacent said cam faces, the bearings engaging said bolt, the rear end portions of said jaws being bifurcated, pins fastened to the bifurcations and extending upon opposite sides of said jaws, rollers mounted upon said pins within the bifurcation, springs connecting the ends of pins of opposite rollers, a cam movably held within the casing and adapted to engage the cam faces of the jaws and the rollers, operating handle levers for forcing said cam for- 120 125 130

- ward, and means for loosely holding said handle levers in position, thereby permitting rotation of the jaws, casing, and cam independent of movement of the handle.
- 5 8. A device of the kind described comprising movable jaws, rollers carried at the inner ends of said jaws, springs adapted to spread the outer ends of the jaws, a casing supporting said jaws, a cam block comprising a V-shaped cam portion adapted to engage said rollers and a disk portion, said cam block being loosely held in the casing, means for preventing rotation of the cam block within the casing, a sleeve rotatably mounted upon the
- 10 disk portion of the cam and within the casing and having rearwardly extending lugs, and operating handles having cam portions
- 15

loosely held between said lugs and loosely in engagement with the disk of the cam block, as and for the purpose set forth. ²⁰

9. A device of the kind described comprising a pair of operating cam lever handles, a casing, gripping jaws carried by said casing, a cam block loosely held in the casing adapted to force the gripping jaws together, the cam portions of the lever handles actuating said cam block, and means for loosely connecting said handles to the casing, thereby permitting rotation of the casing independent of movement of the handles. ²⁵
